BROODER STOVE

John R. Heatwole, Winchester, Va., assignor
to Snapp Foundry Inc., Winchester, Va.

Application July 23, 1935, Serial No. 32,790

4 Claims. (Cl. 236—6)

My present invention relates to improvements in brooder stoves, and particularly to automatic means in combination with a thermostat for controlling the draft to the stove. In carrying out my invention I provide a control device that is simple in construction, inexpensive in cost of production, which may be assembled with facility, and which may be installed for use with facility.

The automatic control device is designed as an auxiliary in connection with an indirect draft, to supplement, or to be substituted for the direct draft usually employed in the stove, and while the control device is adapted for use with stoves burning various fuels, it is especially designed for use with wood-burning stoves. By the utilization of the device of my invention, after the fire has been started in the stove, the predetermined heat or temperature will automatically be maintained for required periods of time without necessity for attention.

The invention consists in certain novel combinations and arrangements of parts as will hereinafter be more fully set forth. In the accompanying drawings I have illustrated one complete example of the physical embodiment of my invention, but it will be understood that changes are contemplated and may be made in the exemplifying structure, within the scope of my claims. Figure 1 is a sectional view of a brooder equipped with the device of my invention. Figure 2 is a top plan view of the control device; Figure 3 is a detail sectional view; and Figure 4 is a detail view of the thermostat.

In order that the general arrangement and relation of parts may readily be understood I have shown in Figure 1 a well known type of brooder having the centrally located stove 1, which is preferably fashioned of sheet metal in desired shape, either rectangular or cylindrical. The bottom of the stove, as indicated at 2, is provided with a lining or base of heat-insulating material of suitable nature, and if desired, the stove may have feet F to slightly elevate it from a floor to provide for circulation of air under the stove and protection to the floor against heat from the stove.

The cast metal top of the stove is provided with the usual chimney or smoke pipe 3 and the outlet port 4 thereto, and a lid 5 is hinged to the top at 6 to cover the hole through which fuel is fed to the stove. Preferably the stove is of the wood-burning type, but it will be understood that fuel other than logs may be provided for combustion and heating purposes, and a clean out door 7 is hinged to the side of the stove at a suitable point near its base for removal of ashes,

and for intake of air to aid combustion when starting the fire.

The canopy 8, which is preferably fashioned of sheet metal, with sloping walls, extends around the stove as a hover for the chicks, and an upwardly and outwardly flaring guard wall, also of sheet metal, as 9, is also attached to the stove, near its base, to prevent the chicks from being crowded against the heated walls of the stove.

It will be understood that the stove and the canopy may be fashioned of various materials, in different sizes and shapes, and the proportions of the different parts of the appliance may be varied for use under different conditions of service.

Near the base of the stove, and preferably diagonally opposite to the upper outlet hole or smoke port 4 of the stove-top I provide an intake port 10 of substantially less area than the outlet hole 4, and on the exterior of the stove wall I attach an elbow casting 11 which opens through the intake port to the interior of the stove. The casting is attached to the stove in suitable manner, as by means of an attaching flange 12 and screws 12', and the upper outer leg 13 of the casting is formed with a smooth horizontal top edge which performs the functions of a valve seat in the control of and admission of air through the elbow to the interior of the stove.

The part 13, or valve seat end of the casting 11 projects upwardly through the bottom of a control drum 14, the bottom 15 of the drum being provided with a central opening to accommodate the pipe 13, and lock nuts 16, 16 are threaded on the pipe 13, below and above the bottom 15 to securely retain the drum on the pipe, and with the top edge of the pipe elevated slightly above the bottom of the drum and the inner locking nut 16.

The drum, which is preferably fashioned of sheet metal and of cylindrical shape is located exterior of and adjacent to the base portion of the stove, and the removable top 17 of the drum fastened thereto by screws 18 or bolts, is provided with an annular series of circular holes or openings 19, which, when open readily permit currents of air to flow from the atmosphere to the interior of the drum, as indicated in the drawings. When these openings or holes 19 are closed, draft or air or circulation of air currents to the interior of the drum, is of course cut off.

In the central portion of the drum is mounted, loosely, a vertically disposed pin 20 having its opposite ends threaded, and this pin is of sufficient length to project at its lower end down into the valve-seat mouth of the pipe 13, and

at its upper end to project through a hole in the center of the top of the drum. A sheet metal disk as 21 having a center opening is loosely mounted on the pin, within the drum, and this disk, which is adapted to seat on the top edge of the pipe 13, is of sufficient area to simultaneously close the ports or holes 19 in the top 17 of the drum.

When the disk-valve 21 is seated on the top of the pipe 13, the latter is effectually closed, except for a series of small auxiliary or idling ports 22 arranged around the center opening of the disk-valve, and these idling ports supply sufficient air to support combustion in the stove to prevent accumulation of smoke or gases within the stove, when the draft thereto is cut off.

The disk valve 21, with its central opening is loosely mounted on the pin 20, and it may be supported on the pin and prevented from displacement by means of an adjusting nut 23 threaded on the lower end of the pin, beneath the disk valve.

On the upper threaded end of the pin, exterior of the drum another adjusting nut 24 is threaded, and these two adjustable nuts on the pin are regulated to govern the movement of the disk valve between the under face of the top 17 of the drum, and the upper seat or top edge of the pipe 13.

30 The upper end of the threaded pin 20 passes through a slot 25 in the long arm of a lever 26, which lever extends outwardly from the stove, and is pivoted at 27 in a bracket 28, which bracket is attached at its opposite ends, by screws to the drum 14 and to the overhanging portion of the canopy 8 and is located directly beneath the lever 26.

By means of the adjusting nut 24 that is located above the lever, and the adjusting nut 23 that is located below the disk-valve 21, the pin and the valve may be vertically adjusted with relation to the lever and the ported top 17, as well as the valve-seat of the pipe 13, to assure accuracy and efficiency in controlling the admission of air through the drum and through the pipe 13 to the interior of the stove.

50 The control lever 26 is operated through the instrumentality of a suitable thermostat 29, here shown as of the well known wafer type, containing a suitable fluid or liquid that is expandable under heat to operate the thermostat, and the latter is mounted at 30 on the bracket 28 below the lever and spaced a suitable distance from the fulcrum 27 of the lever.

55 The lifting power or force of the thermostat, as it expands under heat, is applied to the lever through the use of a pin 31, secured to the lever by the wing nut 32, and the pin is fashioned with a round head 33 that rests on and in contact at all times with the upper wall of the wafer or thermostat.

This thermostatic control device, preferably radiates from the stove body outwardly from the center of the brooder to the edge of the canopy, and a wire screen, or other guard 34 may be placed over the control device to prevent the chicks from roosting or perching on the device.

70 The thermostat is set for a predetermined degree of temperature, to control the lever and the valve-disk mounted on the pin of the lever, and the normal position of the valve 21 may be adjusted to various conditions. It will readily be apparent that as the thermostat expands, the lever, or the free end of the long arm of the lever is lifted, until the full force of the thermo-

stat is employed to lift the disk valve against the underside of the top 17 and close the ports 19. When the heat radiated from the stove reaches this excessive degree of temperature, the intake of air for supporting combustion is cut off, entirely, and in the absence of flow of air to the interior of the stove causes a reduction of the excessive heat until the temperature again falls to the predetermined normal point. When the thermostat is contracted, the lever 26, by gravity action, rests upon and is supported by the head 33 on the thermostat, and of course the fulcrum 27 also supports the lever, and the disk-valve may be adjusted on its pin to close, or to partially close, the inlet port of the pipe 13.

10 The auxiliary idling ports 22 of the disk valve are of such area as to provide or admit only sufficient air currents to the interior of the stove as to prevent extinguishing the fire, but to prevent a roaring blaze or intense heat within 20 the stove.

15 The use of the disk-valve within the interior of the drum, and below the inlet ports 19 of the drum, permits the valve to function with either the perforated top of the drum or the intake 25 port of the pipe 13. Thus, through accident from any cause, should the thermostat fail to operate, the lever falls by gravity, and the pin and valve fall with the lever, the latter automatically closing the pipe 13 except for the idling ports 22. 30 Or, should the expanded thermostat fail to contract from any cause, the lever may remain in uplifted position, but the lever holds the disk-valve against the under side of the top of the drum to close the ports 19, thus preventing un-controlled draft of air through the control device. If and when the lever falls, its full movement permits the valve disk to close the port of pipe 13.

20 Thus, the heat of the stove is automatically 40 controlled in a reliable manner to maintain the predetermined temperature at which the thermostat is set, and the combustion in the stove is controlled by the draft control device.

25 In starting a wood fire in the stove, it is preferable to use the direct draft through the open door 7, or in the event green wood is supplied to the stove as fuel, the direct draft is employed, to insure sufficient air to support combustion in the stove, and the smoke and products of combustion 50 are carried off through the chimney or smoke pipe 3.

30 After the fire is properly started and combustion is supported within the stove, the door 7 is closed to shut off the direct draft, and the indirect draft of my control device is then utilized for maintaining the fire. With a good fire burning in the stove, and a sufficient supply of wood, or other fuel, the brooder-stove may be left over-night and the control device for the supply of air 60 automatically and reliably maintains the proper degree of temperature under the canopy and around the stove for the preservation of the chicks.

35 The control device may be manufactured as a 65 part of the brooder-stove, or it may be attached for use with brooders already in use.

Having thus fully described my invention, what I claim as new and desire to secure by Letters Patent is:—

40 1. The combination with a stove having a draft inlet port and an inlet pipe connected therewith having a valve-seat, of a control drum enclosing the valve seat and having air inlet ports, a valve located within the drum between the valve 75

5 seat and the inlet ports, a valve stem reciprocable in the drum and supporting said valve, and a thermostatic control device adapted to reciprocate said stem and valve for controlling the opening of the inlet ports, and said valve adapted to close the valve seat upon failure of the thermostatic control device to function.

10 2. In a thermostatic stove-draft control device, the combination with a drum having inlet and outlet ports in opposed walls thereof, of a reciprocable valve stem, a valve, and means for suspending the valve on said stem between the inlet ports and outlet port, an operating lever for lifting the stem, and a thermostat for actuating said 15 lever for controlling the opening of the inlet ports, and said valve adapted to substantially close the outlet port upon failure of the thermostat to function.

15 3. In a draft control device, the combination with a drum having a lower outlet port and an upper inlet port, of a valve stem reciprocable in the drum, a valve mounted on the stem between said ports and an adjusting nut on the stem supporting the valve, a second adjusting nut

5 mounted on the stem exterior of the drum, an operating lever having its free end loosely engaging the stem beneath the exterior nut, and a thermostat for operating said lever and controlling the opening of the inlet ports, and said valve adapted to substantially close the outlet port upon failure of the thermostat to function.

10 4. In a draft control device, the combination with a drum having a lower outlet port and an upper inlet port, of a disk-valve between said ports and provided with a central opening, a valve stem reciprocable in the drum with its lower end passed through said opening, an adjusting nut threaded on the stem below the valve, a second adjusting nut threaded on the upper end of the stem exterior of the drum, a pivoted operating lever, said lever having a slotted end mounted on the stem between the drum and the exterior nut, and a thermostat for operating the lever, whereby the valve is adapted to control the opening of the 15 inlet port and also adapted to substantially close the outlet port upon failure of the thermostat to function.

JOHN R. HEATWOLE.
